(57) **CLAIM**

The ornamental design for an earpiece as shown and described.

DESCRIPTION

FIG. 1 is a front-bottom-right perspective view of an earpiece according to the claimed design.

FIG. 2 is a rear-bottom-left perspective view of the earpiece.

FIG. 3 is a bottom view of the earpiece.

FIG. 4 is a top view of the earpiece.

FIG. 5 is a rear view of the earpiece.

FIG. 6 is a front view of the earpiece.

FIG. 7 is a left side view of the earpiece; and,

FIG. 8 is a right side view of the earpiece.

The broken lines in the drawings illustrate portions of the earpiece that form no part of the claimed design.
